UNITED STATES PATENT OFFICE.

JAMES A. TILDEN, OF HYDEPARK, MASSACHUSETTS, ASSIGNOR TO HERSEY MANUFACTURING COMPANY, OF SOUTH BOSTON, MASSACHUSETTS, A CORPORATION OF MAINE.

REGISTER.

SPECIFICATION forming part of Letters Patent No. 779,056, dated January 3, 1905.

Application filed July 11, 1904. Serial No. 216,108.

To all whom it may concern:

Be it known that I, JAMES A. TILDEN, a citizen of the United States, residing at Hyde-park, in the county of Norfolk and State of 5 Massachusetts, (whose post-office address is as above,) have invented certain new and useful Improvements in Registers, of which the following is a specification.

My invention relates to registers, it being 10 particularly adapted for use in connection with water-meters. Apparatus of this character is frequently employed under such conditions that the index members representing the highest integers are moved only after considerable 15 intervals, and since the interiors of the registers are more or less exposed to the influence of moisture and liable to become corroded this causes their associated gearing to stick and fail to register. To prevent this by 20 maintaining a constant movement between said gearing and its support during the operation of the register is the principal object of my invention.

In the accompanying drawings, Figure 1 is 25 a side elevation of one embodiment of my invention, parts being broken away; and Fig. 2 is a similar view looking from the right in Fig. 1.

Similar characters of reference indicate like 30 parts throughout both figures of the drawings.

The numerals 10 and 11 designate lower and upper register-plates, respectively, which are shown as separated by suitable posts 12. 35 Through a bearing 13 in the lower plate extends a driving-spindle 14, which also has a bearing in the upper plate and projects through the same, it being provided at its outer end with an index-hand 15. Upon this spindle, 40 adjacent to the inner side of the plate 11, is secured a gear 16, which meshes with a pinion 17, fast upon a shaft 18, journaled in the plates and carrying a worm 19. Meshing with the worm is a gear 20, fixed upon an index-shaft 45 21, which is preferably rotatably mounted in brackets 22 22, secured near opposite sides of the plate 10. Mounted upon the shaft 21 is a series of index members or wheels having nu-

merals visible through an opening 22^a in the upper plate in the ordinary manner, that indicated by the numeral 23 representing the units and lying next to the gear 20 and being fast upon the shaft. The remaining wheels 24 turn loosely upon the shaft, and each wheel, beginning with the inner side of the units- 55 wheel, has a depression formed between walls 25 25, extending outwardly from the edge of a disk 26 and corresponding to two teeth of a mutilated gear. Upon the opposite side of each adjacent wheel is fastened a continuous 60 gear 27.

Extending in proximity with the edges of the index-wheels and being conveniently journaled in the brackets 22 is a gear-shaft 28, carrying loose upon it and interposed between the 65 index-wheels gearing members G, having two sections, (designated as 29 and 30.) The first of these has quite widely - separated teeth adapted to engage the walls 25, and between these teeth are spaces to receive the edge of 70 the disk. The second is in the form of a pinion meshing with the gear 27. This gearing operates to successively advance each wheel one division for a complete rotation of the preceding wheel to register the number of rotations of the driving-spindle in a manner now perfectly familiar in the art and which need not be particularly described. It will be evident that in the absence of some special provision 75 the last member G will rotate upon the supporting-shaft only after what may be a very long interval, in which the parts might become stuck together and the register made inoperative. I render the introduction of such a defect impossible by providing means for 80 constantly rotating the shaft 28 during the operation of the register, this means preferably consisting of a pinion 31, here shown as having a hub 32, fixed upon the shaft in any convenient manner, it being here illustrated as 85 sweat thereto, the layer of solder being indicated at 33. This pinion in the present instance meshes with the gear 20, which is always in operation during the movement of the driving-spindle. In this manner the shaft 90 28 is rotated within all the gearing members 95

G upon even the slightest movement of the register mechanism and all danger of sticking by corrosion or otherwise is obviated.

Having thus described my invention, I claim—

1. A register comprising movable index members, a shaft situated adjacent thereto, gearing for the index members rotatable about the shaft, and means for continuously rotating said shaft during any movement of the index members.

2. A register comprising a shaft, a plurality of index members movable about the shaft, a shaft journaled adjacent to the index members, gearing for the index members rotatable about the last-named shaft, and continuously-coacting gears fixed to the index-shaft and the gear-shaft respectively.

3. A register comprising a shaft, a plurality of index-wheels mounted upon the shaft, inter-

mediate gears movable with the index-wheels, a second shaft, gears loose upon the second shaft and coacting with the index-gears, and continuously - intermeshing gears fastened upon the index-shaft and the gear-shaft respectively.

4. A register comprising movable index members, a shaft situated adjacent thereto, gearing for the index members rotatable about the shaft, a driving-spindle, a gear for the index members connected with said driving-spindle, and a pinion upon the shaft meshing with the last-named gear.

Signed at Boston, in the county of Suffolk and State of Massachusetts, this 7th day of July, 1904.

JAMES A. TILDEN.
